UNITED STATES PATENT OFFICE.

RICHARD WHITAKER, OF NEW BRUNSWICK, NEW JERSEY, ASSIGNOR TO
THE NEVERSLIP MANUFACTURING COMPANY, OF SAME PLACE.

DESIGN FOR A HORSESHOE-PAD.

SPECIFICATION forming part of Design No. 29,580, dated November 1, 1898.

Application filed October 6, 1898. Serial No. 692,859. Term of patent 7 years.

To all whom it may concern:

Be it known that I, RICHARD WHITAKER, a citizen of the United States, residing at New Brunswick, in the county of Middlesex and State of New Jersey, have invented and produced a new and original Design for Horseshoe-Pads; and I do hereby declare the following to be a full, clear, and exact description of the same, reference being had to the accompanying drawings, forming a part thereof.

In said drawings, Figure 1 is a bottom face view of a horseshoe-pad embodying my new design. Fig. 2 is a vertical cross-section on line $x-x$ of Fig. 1.

The object of my invention is to provide a design for horseshoe-pads; and to this end said invention consists in the design as herein set forth and shown.

The leading features of my design for a pad consist in a horseshoe-shaped front portion terminating in a heel portion of greater width, the front of said heel having two scallops of the same length, the horseshoe-shaped cavity in the pad terminating against said two scallops and containing two concentric rings, with a diamond within the inner ring, the heel be-

ing provided also with two wings tapering toward the front, and its face provided also with rows of semispherical projections. 30

The pad consists of a horseshoe-backing A, to which is secured the pad proper, B, the front portion of which is horseshoe shape and is beveled inwardly and outwardly and terminates in the heel portion C. The front of 35 said heel has two beveled scallops $c-c$, having their dividing-line in the axis of the heel, and two wings c^2-c^2 , tapering toward the front. The face of the pad is provided with rows of semispherical projections b , and within the 40 cavity of the pad and projecting in relief from its inner wall are two concentric rings d , with a diamond e within the inner ring.

Having fully described my invention, I claim— 45

The design for a horseshoe-pad as herein shown and described.

In testimony whereof I affix my signature in presence of two witnesses.

RICHARD WHITAKER.
